ADVERTISING DISPLAY FIXTURE

Edwin R. Dean, Minneapolis, Minn.

Application January 27, 1940, Serial No. 316,041

6 Claims. (Cl. 40—125)

This invention relates generally to the class of advertising devices and pertains particularly to improvements in advertising fixture mountings.

The present invention has for its primary object to provide an improved mounting for advertising fixtures or other similar articles by means of which a number of different articles such as placard supporting frames and the like may be readily mounted in various positions upon a wall, post or other suitable supporting structure, the fixture including demountable units upon which such placard supports may be secured at selected elevations or in selected positions, which units in themselves are so designed that they will not detract from the appearance of a wall or column upon which they may be secured.

Another object of the invention is to provide a novel advertising fixture employing a pair of permanently mounted elements and auxiliary elements designed to be attached to and supported by the permanent elements, which auxiliary elements may be used one with the other upon the permanent elements or mounted singly upon such permanent elements for the support of a display or advertising unit.

Another object of the invention is to provide an advertising fixture employing pairs of units adapted to be fixed to a wall, post or other supporting structure together with interchangeable units either of which may be readily detachably secured to said fixed units by means of hook and eye coupling means whereby it is possible, after placing such pairs of fixed units in desired positions in a business establishment, to distribute the interchangeable units to the locations where the fixed units are mounted and mount the same easily and quickly upon the fixed units for the support of display material or advertising material.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

In the drawing:

Fig. 1 is a view in perspective illustrating two pairs of fixed units each carrying a detachable unit, the fixed units being shown mounted upon

a post or column, a portion of one of the units being in vertical section.

Fig. 2 is a sectional view taken substantially on the line 2—2 of Fig. 1.

Fig. 3 is a sectional view on the line 3—3 of Fig. 1.

Fig. 4 is a view in front elevation of one of the fixed units.

Fig. 5 is a view in perspective of a portion of one of the detachable or interchangeable units showing the hook engaging eye thereof.

Fig. 6 is a view in perspective of a modified form of bar unit designed to be supported by a pair of rosettes.

15 Referring now more particularly to the drawing, the numeral 1 generally designates a supporting structure in the form of a post or column upon which the structure embodying the present invention is shown mounted.

20 The advertising or display fixture constituting the present invention comprises a pair of fixed units each generally indicated by the numeral 2. Each of these units 2 consists of a plate member 3 which is designed to be permanently secured 25 to the face of the supporting structure, it being provided with integral pins 4 projecting from one face and adapted to be forced or driven into the material of the supporting structure so as to hold the plate against turning. The central portion 30 of the plate 3 has an aperture 5 designed to receive a securing element such as the screw 6.

35 Detachably secured to the face of the plate 3 is a button 7 which is here shown as being built up to have a substantial height but gradually decreasing in diameter from the bottom part to the upper or outer part and formed integrally with this button and extending from the center of the same is a hook 8 which is directed upwardly when the element is mounted in working position.

40 The plate 3 is provided with suitable threaded apertures, not shown, for the reception of screws 9 which are passed through the button 7 and by which the button is detachably secured to the base plate 3. The whole unit made up of the button 7 and the base plate 3 forms what might be termed a supporting rosette. These rosettes are secured to a wall, post or other suitable supporting structure in vertically spaced pairs as they are shown in Fig. 1, and the units of each pair are spaced apart the same distance as the units of each of the other pairs, so that any pair of supporting rosette units may be made use of for supporting either of the interchangeable units which are generally designated by the numerals 50 10 and 11.

The interchangeable or removable unit 10 is in the form of a relatively long flat bar 10' preferably of channeled form, rounded off at each end as indicated at 12, for neatness, and having upon the inner channeled side two plates 13 in each of which a hook receiving eye 14 is formed. These plates are, of course, spaced apart so that the eyes 14 thereof will be separated a distance equal to the distance between the hooks 8 of a pair of supporting rosettes and it is preferred that the pair of plates be disposed both at one side of the transverse center of the bar so that when the bar is mounted upon a pair of fixed rosette units, as shown in Fig. 1, the major portion of the same will extend above the upper one of the fixed units.

The bar 10' has a front face and two side faces as shown, and there are secured to the bar in three different planes groups of three hooks, each of which is indicated by the numeral 15, one hook of each group being upon the forward face or side of the bar and each of the other two hooks of the group being upon a side face of the bar. The groups of hooks 15 are separated longitudinally of the bar by the same distance as the hooks of each pair of fixed rosettes.

The shiftable or interchangeable unit 11 is in the form of a frame 16 having a slot 17 through its top bar for the insertion into the frame of a suitable advertising material carrying placard 18, the edges of such placard being engaged in grooves 19 in the inner sides of the other three bars of the frame.

Secured to one vertical side bar of the frame 16 is a pair of plates 20, each of which has an eye 21 therein for the reception of a hook 8 of a fixed rosette unit or a hook 15 of one of the groups of hooks carried by the bar 10'.

The front side or face of the bar 10' may have secured thereto a base plate 22 of an angularly extending flagstaff socket 23, by means of screws 24. Obviously this flag socket may be removed if desired, without interfering with the use of the other units as a complete advertising fixture.

In the use of the present structure, the pairs of fixed rosette units 2 are mounted, as previously stated, in desired locations as permanent fixtures to have attached thereto either the placard carrying unit 11, through the medium of the eyed plates 20, or a bar 10' which may carry the flagstaff socket 23 or other display elements equipped with suitable eyes for engagement with a vertically spaced pair of hooks 15. In addition the unit 11 and bar 10' may be mounted together upon a single pair of supporting rosettes 2 as, for example, the bar 10' may be mounted initially upon the rosettes as shown in Fig. 1, and the placard carrying unit may then be mounted upon the bar by engaging a pair of vertically spaced hooks 15 in the eyes 21 of the unit frame 16. It will also be readily apparent that by using the unit 11 in association with the unit 10', the placard carrying unit may be supported to extend outwardly from the front side of the bar 10' or to extend laterally from either of its side faces. Such lateral disposition of the placard carrying unit 11 might be advantageously made where the rosette units are mounted upon a circular column of relatively small diameter or a rectangular column of small cross-sectional design which would result in the major portion of the placard carrying unit 11 extending a substantial distance outwardly from the supporting column to be readily observed from both sides.

In Fig. 6 a modified form of bar unit is shown and generally designated by the numeral 25,

which bar unit is designed to be supported upon a vertically spaced pair of the rosette units 2 in the same manner as the bar 10. The unit 25 is designed for use in connection with bodies of wood or similar material which are to be placed on display and which are of a character to permit screws to be inserted therein and to this end the bar, which is of channel form as shown, is provided with a series of longitudinally spaced screw apertures 26 formed through the web portion of the bar. Extending across the edges of the flanges 27 are two spaced apertured plates 28 of the same form as the plate 20 shown in Fig. 5 and separated the same distance as such plate so that the slots thereof may receive the hooks of a pair of vertically spaced rosettes 2. When the bar unit 25 is used screws will be extended through the apertures 26 into the body which is to be mounted for display so that such body will be firmly attached to the bar and the bar may then be mounted upon a pair of rosettes in the same manner as the bar 10 is shown mounted. This bar unit 25 is illustrated as being relatively short or of approximately half the length of the bar 10, but it will be readily apparent that it may be made of greater length, if desired.

From the foregoing, it will be apparent that there has here been disclosed a novel and improved form of advertising unit which, because of its novel construction, may be advantageously used in numerous locations without having to employ any accessories other than the ones particularly illustrated and described.

What is claimed is:

1. An advertising unit of the character described, comprising in combination a pair of hook carrying units adapted to be fixed in spaced relation to a support, and a display carrying unit including a channel portion having a length sufficient to bridge the space between said pair of units and eyed members secured across and opening into the channel and spaced to receive the hooks of the pair of units whereby the display carrying unit may be supported by the pair of fixed units.

2. An advertising fixture of the character stated, comprising in combination a pair of hook carrying units designed to be secured in spaced relation to a supporting structure whereby the hooks will extend forwardly therefrom, a second unit having a length sufficient to bridge the space between said hook units, said second unit having a pair of eyes formed and spaced to receive the hooks of the fixed units and be held thereby forwardly from the supporting structure, a pair of longitudinally spaced hooks carried by and projecting from and perpendicularly to the second unit, a third unit designed to carry the display material and having an edge portion of a length sufficient to bridge the space between the said pair of longitudinally spaced hooks of the second unit, and a pair of eyes carried by the said edge portion of the third unit in a plane transversely to the plane of the third unit to receive the hooks of the second unit and be supported by the last-mentioned hooks extending outwardly from the second unit and from said structure.

3. An advertising fixture of the character stated, comprising in combination a pair of hook carrying units designed to be secured in spaced relation to a supporting structure whereby the hooks will extend forwardly therefrom, a second unit having a length to bridge the space between said hook units, said second unit having a pair

of eyes formed to receive the hooks of the fixed units, a plurality of groups of hooks carried by the second unit, the hooks of each group being in the same plane transversely of the unit and extending in different directions therefrom, the hooks of one group coating with the hooks of an adjacent group to form pairs of hooks spaced longitudinally of the second unit, a third unit constructed to support display material, and means providing a pair of spaced eyes on said third unit arranged to receive the hooks of one of the said pairs carried by the second unit.

4. An advertising material display fixture, comprising in combination a pair of units each carrying a hook, said units being secured in spaced relation on a supporting structure, and a display material carrying unit having a length sufficient to extend across the space between the hooks of the first units for connection therewith for the support of the display material unit upon the pair of hook units, said display material unit comprising an open frame formed to receive a placard and having a side portion consisting of spaced parallel members between which an edge of the placard engages, and plate members secured across the parallel members and having eyes for the reception of said hooks. 25

5. An advertising unit of the character described, comprising in combination a pair of hook carrying members adapted to be secured in spaced relation to a support and a display supporting unit comprising a channel bar having a web portion and flange portions, the web portion having apertures therethrough for receiving securing elements engaging the display and the web portions being connected by eyed plates spaced apart and formed to receive the hooks of said members.

6. An advertising unit, comprising in combination a pair of hook carrying units adapted to be secured in spaced relation to a support with the hooks projecting forwardly with relation to the face of the support, and a display supporting unit comprising a member having sufficient length to bridge the space between the hooks, said member being of a construction to form a lengthwise extending channel and flat eyed members secured across and spaced along and opening into the channel and spaced apart sufficiently to receive the pair of hooks, the hooks extending into the channel. 20
